UNITED STATES PATENT OFFICE.

CHARLES J. KOENIG, OF NEW BALTIMORE, MICHIGAN.

FOLDING STOOL OR CHAIR.

Application filed May 19, 1921. Serial No. 470,779.

To all whom it may concern:

Be it known that I, CHARLES J. KOENIG, a citizen of the United States of America, residing at New Baltimore, in the county of Macomb and State of Michigan, have invented certain new and useful Improvements in Folding Stools or Chairs, of which the following is a specification, reference being had therein to the accompanying drawings.

10 This invention relates to improvements in folding stools or chairs, pertaining more particularly to such devices in which the support and seat are adapted to be connected together for use and separated when collapsed under non-use conditions.

15 The essential characteristics of a structure of this type are that when in service the structure will not only support the weight without liability of collapsing and be free from liability of tilting over, but these results must be obtained without sacrificing compactness when folded and by the use of a structure that is of relatively light weight and readily changed from service to collapsed condition.

20 Various attempts have been made to secure these results, but in the various forms of which I am aware, one or more of these essential features have been sacrificed to secure the remainder, thus setting up conditions where the seat is capable of but limited use in that the parts will not sustain the average load; or the structure is so complicated as to require extensive manipulation 25 or careful adjustment of parts, requiring expertise in setting up or taking down the stool; or the structures are such as to provide a comparatively large package when the stool is collapsed and arranged to be transported; or extreme rigidity will limit use 30 through inability to compensate for inequalities in the surface on which the stool is placed, thus setting up conditions of tilting; or the structure may be of such a complicated character as to set up high cost of manufacture conditions.

35 The present invention is designed to produce a structure having these essentials and which eliminates these undesirable features, and at the same time provide a construction which is neat and attractive in appearance, durable in construction, simple and efficient in operation and which can be manufactured at a comparatively low cost.

40 To these and other ends, the nature of which will be readily understood as the in-

vention is hereinafter disclosed, said invention consists in the improved construction and combination of parts hereinafter more fully described, illustrated in the accompanying drawings, and more particularly pointed out in the appended claims.

45 In the accompanying drawings, in which similar references indicate similar parts in each of the views,

Figure 1 is a view in elevation of one embodiment of the invention set up for service, parts being broken away for clearness.

Fig. 2 is a sectional view taken on line 2-2 of Fig. 1.

Fig. 3 is an end view of the support portion when collapsed.

Fig. 4 is a detail view showing one form of device which may be employed to detachably connect the seat and support portions.

Fig. 5 is a sectional view taken on line 5-5 of Fig. 1.

Fig. 6 is a perspective view of the support when partially opened.

Fig. 7 is a side elevation of the support so when collapsed.

Fig. 8 is a detail sectional view taken on line 8-8 of Fig. 7.

The support, indicated at A, is formed with a plurality of legs a, preferably four 45 in number, each leg being formed of two sections 15 and 16, these being secured together in hinge relation, a simple arrangement being by connecting complementally formed section ends by a pintle 17. The 50 legs are preferably formed of metal—aluminum, for instance,—and the sections have cross-sections such as to permit of telescoping characteristics. For instance, section 15, which serves as the lower or foot section is 55 formed with a longitudinal groove or recess 15^a on its outer side between the foot 15^b and its knuckle formation 15^c, groove 15^a being adapted to receive the web 16^a of section 16, the cross-section of the latter being 60 more or less T-shape, the laterally extending portions being adapted to overlie outer face portions of section 15 when the support is collapsed, as indicated, for instance, in Figs. 6 to 8, thus producing a leg formation 65 in which the sections are each of maximum strength by reason of their cross-sections, and which can be brought into a position to occupy a minimum of space.

70 Sections 15 and 16 are connected together by a sectional link formation, indicated at 18, the outer ends being pivoted to the re-

- specive sections and to each other, the sections having projections to locate the pivot points outside of the section portions which have the telescoping relation. The link formation 18 is not designed essentially for supporting purposes, although, when alined, the link sections serve this purpose to an extent; the formation, however, does limit the extent of opening movement of the sections so as to prevent the section 16 from collapsing inwardly when in service, thus permitting the use of a simple hinge formation at the point of connection of sections 15 and 16.
- 15 The hinge ends of sections 15 are each provided with a pair of ears 15^a adapted to receive a pintle 19, said pintle being spaced from the end of the section a greater distance than pintle 17, the ears being located 20 to locate pintle 19 at the inner side of the section. Pintle 19 serves to unite the leg formation to a connecting element 20, shown as in the form of a cross, the arms of which are arranged in two groups, the groups differing as to length of the arm from the point of meeting of the several arms. For instance, arms 20^a are of less length than arms 20^b, as shown in Fig. 3. As a result, the legs which are secured to these arms extend 30 closer to the adjacent arms than do the legs secured to arms 20^b.
- A preferred arrangement in this respect is that shown in Fig. 3 in which, for instance, the leg formations *x* are pivoted to the cross in such way that when the lower ends are moved outwardly, the upper or hinge ends come into contact with each other above the cross, the result being that these upper ends thus brace each other and limit 40 the independent outward movement of a leg; independent movement on the pintle may occur, but this would shift the position of the opposite leg, since each leg section 15 is mounted in such manner as to locate 50 its fulcrum at an intermediate point and thus has somewhat the characteristics of a lever of the first order; outward movement of the lower end of one of the legs would cause its opposite end to apply pressure 55 against the short arm of the lever produced by the opposite leg and tend to move the longer arm inward. This arrangement, in the presence of a load applied from above might appear to set up shearing strains on 60 pintles 19, but this is not only prevented by the ability to use pintles of comparatively large size, but in addition, opposing legs are connected by link formations 21 which would tend to reduce the possibility of spreading action.
- On the contrary, legs *y* are connected to the cross in such manner that when these legs are spread the short arm of the lever—the hinge end—comes into contact with the 65 side faces of the contacting ends of legs *x*,

so that legs *x* provide the brace for legs *y*. And if desired, the side faces of legs *x* may be cut-away, as at 22 in Fig. 2, to receive the ends of legs *y*, thus tending to set up a stop condition—an interlock—between the two sets of legs such as to limit this movement of legs *x* to any point desired, this depending upon the amount of play permitted by the widths of the recesses 22.

As will be understood, the arrangement thus provides for bracing one leg formation by another leg formation, a construction which, because of the sturdy leg formation permitted, sets up an exceedingly strong mechanical construction adapted to support the load weight and yet, if desired, permit of sufficient flexibility as to allow the legs to properly seat on uneven ground without material liability to tilt.

This bracing action will be readily understood from the fact that while sections 15 and 16 are hingedly connected together, the connection is not only independent of the hinge connection between the formation (the connected sections 15 and 16) and the cross 20, but the latter pivotal connection is below that between the sections of the formation. As a result there is a tendency to set up the conditions of a lever of the first order in connection with section 15 when weight is placed on the seat or pressure exerted in the direction of length of section 16; the movement of section 15, however, is limited by the contact of its upper end with the adjacent leg structures—the condition produced by the action of the cross 20—and the applications of pressure is also limited by the same means, the contacting relation between adjacent sections applying with respect to both sections 15 and 16 at the hinging point. Hence, the possibility of shearing strains on pivots 17 is substantially eliminated, permitting the use of pintles of an ordinary size—with a corresponding reduction in the size of the hinge—without liability of the seat or stool collapsing through breakage at the hinge connection 17, even though the weight on the seat be comparatively large.

As will be understood, the arrangement is such that the pivot connections for the sections of opposing formations, move toward each other when the stool is being placed in service position, due to the fact that the point of hinging connection of the several formations with the cross-member is between the point of pivotal connection and the lower end of the section—in other words, the fixed connection (the hinge connection between the lower sections and the cross member) is below the section pivots in service position. In the embodiment shown the cross member is located entirely below a horizontal plane extending through the several section pivot points when in serv-

ice position, so that in such position the formations come into actual abutting relation to set up the mutual bracing action referred to. It will be understood, however, that the result would not be materially affected if a portion of the cross-member were extended between the faces shown as abutting, and hence, in employing the term "abutting relation", it is intended to include not only the actual abutting relation shown, but also a relative abutting relation such as would be present if material be interposed between the faces.

The seat portion, indicated at B, is detachably connected to the free ends of sections 16 of the legs, when the latter are shifted to the open position of the leg formation. Any suitable form of seat may be employed, as may be any desired form of connection between the leg and seat. I prefer, however, to employ a structure along the lines of that illustrated in the drawings in which the free ends of the sections 16 are shown as formed T-shaped, the laterally-extending portions being of curved contour, the whole forming a T-head which is adapted to be received within a keeper 23, such as shown, for instance, in Fig. 4, this being secured to the under face of the seat B, shown, in this instance, as of leather, the four keepers being properly positioned to be engaged by the four sections 16 when the latter are in position; since the entrance of the head into the keeper is outwardly, the keepers are positioned to permit this movement, resulting in the seat having a more or less amount of slack intermediate the points of connection and therefore better able to conform to the portion of the body of the user resting upon the seat.

While not essential, I prefer to connect opposite portions of the seat edge below the plane of the keepers, as for instance by straps 24, these extending along edges, but preferably diagonally beneath the seat, these preventing any possibility of the movement of sections 16 to closed position while the seat is in use. If desired, the straps 24 may be omitted and the sections connected by disengageable connections, this differing from that shown only that the connections would be carried by the support instead of the seat.

Since the support can be folded into small compass, the seat can be used as an element to wrap up the support, the straps retaining the wrapped condition, the entire package being compact and of a form such that, if desired, a large number can be packed within a container and readily transported, thus making the construction one adapted for the use of undertakers, caterers, etc., where it is necessary to provide a temporary seating condition and where it becomes necessary to transport a considerable number of structures for use in this connection.

While I have herein shown and described a preferred arrangement and construction, it will be readily understood that changes or modifications therein may be found necessary or desirable to meet the exigencies of use, and I desire to be understood as reserving the right to make any and all such changes or modifications as may be found desirable or essential in so far as the same may fall within the spirit and scope of the invention as expressed in the accompanying claims, when broadly construed.

Having thus described my invention, what I claim as new is:

1. In folding stools or chairs, wherein the seat and seat support are in the form of independent units adapted combinedly to produce the service condition of the stool or chair and are separable to permit folding, a seat support unit including a plurality of sectional leg formations, the sections of each formation being pivotally connected adjacent an end of one of the sections, and an element hingedly connected to the several formations, the hinge connections of the several formations and the element being spaced from the pivot connections of the sections of a formation and located relative to such pivot points as to place the hinge connection below the pivot connection when the support is in service position to cause the pivot points of opposite formations to tend to approach each other to set up a bracing relation between the formations to maintain the support in such service condition.

2. In folding stools or chairs, wherein the seat and seat support are in the form of independent units adapted combinedly to produce the service condition of the stool or chair and are separable to permit folding, a seat support unit including a plurality of sectional leg formations, the sections of each formation being pivotally connected adjacent an end of one of the sections, and an element hingedly connected to the several formations, the hinging connection with each formation being limited to but one of the sections of the formation and having the point of hinging connection spaced from the point of pivot connection of the sections of the formation with the location such as to place the hinging connection below the pivot connection when the support is in service condition, the relative locations of the pivot and hinging connections being substantially similar with each formation and operative to tend to cause the pivot connections of opposing formations to approach each other when the support is in service condition.

3. A seat support unit as in claim 2 characterized in that the connecting element is positioned to permit contact of the pivot connecting portion of one formation with the similar portion of another formation

above the element when the unit is in its service condition.

4. In folding stools or chairs, wherein the seat and seat support are in the form of independent units adapted combinedly to produce the service condition of the stool or chair and are separable to permit folding, a seat support unit including a plurality of sectional leg formations; the sections of each formation being pivotally connected adjacent an end of one of the sections; an element hingedly connected to each of such formations with the element having a configuration to locate alternate formations in opposed relation in the assembly, the element being positioned relative to the pivotally-connected ends of the sections of the formations to permit a section of one formation at such pivot point to contact the similar section of another formation above such element and provide an abutting relation between formations when the unit is in service condition.

5. A unit as in claim 4 characterized in that the element is of cross-form configuration and located below a horizontal plane through the pivot connections when the assembly is in service position.

6. A unit as in claim 4 characterized in that the element is of general cross configuration with an arm of the cross differing in length to that of an adjacent arm.

7. A unit as in claim 4 characterized in that the points of hinging connection are so located that two of the sections will pass into contacting relation with each other and an adjacent section will pass into contact with such contacting sections.

8. A unit as in claim 4 characterized in that the points of hinging connection are so located as to permit movement of alternate sections in the same plane to produce two pairs of opposing formations, the sections of one pair passing into direct contact by such movement, the sections of the other pair passing into contact with the sections of the first pair.

9. A leg formation for folding stool or chair units comprising a pair of sections hingedly connected at an end of each section, one of said sections carrying a foot, the other section having its free end carry-

ing a configuration operative to secure a seat unit thereto when the stool is assembled, said foot section having apertured ears adjacent and spaced from its hinging end to permit attachment to an element adapted to connect a plurality of formations in assembly relation to locate such element intermediate the pivot of the hinged end and the foot of the section, said foot section being substantially U-shape in cross-section to provide a longitudinal recess therein, the other section being substantially T-shape in cross-section to provide a portion entering the recess of the foot section and portions overlying a face of the foot-section, whereby the leg formation, in collapsed form will present a formation of angular contour in cross-section with a plurality of 70 the contour faces provided by each of the sections.

10. A leg formation as in claim 9 characterized in that the free end of the T-shaped section is formed with a T-head adapted 75 to detachably engage a formation carried by the seat and complementary to such head to provide therewith the sole connection between head and seat.

11. In folding stools or chairs, a seat supporting unit comprising a plurality of foldable leg formations connected to permit the formations to move between folded and service positions with each formation formed of a pair of sections pivotally connected 85 and with the connections between the several formations located relative to the pivot connections of the formation sections to produce an abutting relationship between formations, and a seat unit of non-rigid formation, said seat unit and similar sections of the leg formations having complementary 90 means for detachable engagement therebetween when the support unit is in service position, said seat unit having straps operative to maintain the leg sections against movement toward folded position when the seat is in position.

In testimony whereof I affix my signature in presence of two witnesses.

CHARLES J. KOENIG.
